UNITED STATES PATENT OFFICE

2,618,122

TELESCOPIC HYDRAULIC JACK

Jean Louis Gratzmuller, Paris, France

Application August 25, 1947, Serial No. 770,346
In France April 18, 1946Section 1, Public Law 690, August 8, 1946
Patent expires April 18, 1966

4 Claims. (Cl. 60—52)

1

Many proposals have hitherto been made with a view to procuring reliable sealing, guiding and stroke limiting means for telescoping parts of hydraulic lifting jacks.

However, the telescopic parts for such jacks, hitherto proposed, are generally too complicated and necessitate a particularly accurate machining of the various requisite members thereof.

It is an object of the present invention to provide in a hydraulic lifting jack reliable sealing, guiding and stroke limiting means for the telescoping parts, which will be simple in construction and in mounting, and which will do away with the necessity of accurate machining, while possessing the requisite qualities.

The sealing, guiding and stroke limiting means designed according to the present invention include substantially an annular sealing and guiding gasket set suitably interposed between the end portions of each two parts intended to be telescoped into each other, guiding members cooperating with said gasket set for guiding the desired telescopic movements of said parts, and abutment members adapted to support said gasket set and to limit the said telescopic movements.

In the present form, said gasket set is constituted by a metallic collar whose entire lowermost portion is bottomed with an expansible member supported by one of the said abutment means, said collar and expansible member being jammed in between the walls of corresponding telescoping parts, in a recess managed at the end of one of said parts.

Said guiding means are constituted by the metallic portion of said gasket set and by longitudinally superimposed suitable annular members suitably fixed between the walls of respective telescoping parts, some of these members being used at the same time as dirt catchers.

Said abutment means may be constituted either by suitable annular shoulders managed on the walls of respective telescoping parts, or preferably by packstrings of the class including piano strings housed in suitable annular grooves managed in the walls of respective telescoping parts.

The sealing, guiding and stroke limiting means as hereinabove outlined according to the invention are particularly applicable to hydraulic or pneumatic lifting jacks, more particularly to jacks of the telescopic type.

It is, therefore, a further object of the present invention to provide a lifting jack of this kind in which particularly advantageous use is made of the above outlined sealing, guiding and stroke limiting means.

2

Other objects of the present invention will be apparent from the following detailed description and the accompanying drawings in which:

Fig. 1 is an axial sectional view showing a sealing and guiding gasket according to the invention, mounted on a piston displaceable in a cylinder;

Fig. 2 is an axial sectional view showing a hydraulic telescopic lifting jack provided with sealing and guiding gasket according to the invention;

Fig. 3 is an axial sectional view showing stroke limiting and abutment means according to the invention;

Fig. 4 is an axial sectional view showing a modified form of hydraulic telescoping lifting jack provided with sealing, guiding and stroke limiting means according to the invention;

Fig. 5 is a detail showing of a hydraulic mechanism for actuating a lifting jack according to the invention;

Fig. 6 is a detail showing of the mechanism of Fig. 5;

Figs. 7 and 8 are vertical and horizontal sectional views, respectively, of further details of the mechanism of Fig. 5; and

Figs. 9 and 10 are vertical and horizontal sectional views, respectively, showing yet further details of the mechanism of Fig. 5.

Referring first to Fig. 1, designated by 4 is a cylinder in which may slide a piston 3. The lowermost end of this piston is recessed as at 19. Mounted in this recess is a metallic collar 1 bottomed with an annular member 2 made of plastic or other suitable material, the ensemble of 1 and 2 forming a sealing joint. It is readily understood that the metallic collar 1 serves to guide the piston 3 in cylinder 4, while the plastic member 2 insures the tightness between the parts 3 and 4.

Although the members 1 and 2 may be mounted in the recess 19 without being made fast thereto, it is preferable to provide an annular abutment member 20 to prevent the members 1 and 2 from coming off the piston.

Referring to Fig. 2 showing a hydraulic telescopic jack, designated by 15 is the base of this jack, 14 is its housing, 17—18 its pump, while by 16 is designated a controlling device for actuating said pump. Designated by 13 is a first cylinder of the jack, in which may slide a second cylinder 11 acting as piston with respect to the cylinder 13. Designated by 6 is a second piston slidably in the cylinder 11. By 5 is designated the usual screw which is intended to contact, for example, a vehicle axle prior to lifting the jack.

The lowermost ends of the two pistons 6 and

11 are recessed as at 19a and 19b, respectively. On each of these recesses is slid a gasket according to the invention, constituted by a metallic collar 1 and an annular member 2 made of plastic or elastic material. Designated by 10 and 10a are abutment members adapted to maintain the gaskets in place. The pistons 6 and 11 are guided by the annular members 7 and 1, while annular elastic members 8 serve as dirt catchers.

It is clear that with the gasket according to the invention the two pistons may move down to the bottom of respective cylinders, in fact down to the bottom of cylinder 13, so that the volume of the jack may be reduced to its minimum. An abutment 28 serves to push the cylinder 11 into cylinder 13.

Referring to Fig. 3, by 3 is designated a piston located in its cylinder 4. Formed in the piston and cylinder are grooves 33; a piano wire 34 is located in the cylinder groove 33 and a piano wire 35 is located in the piston groove 33. It is clear that when the piston 3 while moving upwards reaches the position shown in Fig. 3, its wire 35 abuts against the wire 34 of cylinder 4.

Referring to Fig. 4, there is shown a hydraulic telescoping jack embodying all the features of the invention. Designated by 15 is the base of this jack, 14 is its outer casing, while 16—17—18 is its pump. Screwed into the base 15 is a first cylinder 13 adapted to receive a second cylinder 11 acting as a piston with respect to the cylinder 13, while said second cylinder 11 is adapted to receive a second piston 6 carrying the usual lifting screw 5. The tightness between the said pistons and the cylinders is insured by gaskets 1—2.

The upward displacement of the piston is limited by an arrangement similar to that illustrated in Fig. 3, said arrangement comprising grooves formed in the cylinder and the piston and adapted to receive piano wires 34 and 35, respectively. The telescopic movements of pistons 6 and 11 in their respective cylinders 11 and 13 are guided on one hand by the upper members 7 and 1 and on the other hand by the lower members 7 and 1. Plastic or elastic rings 8 serve as dust and dirt catchers. An abutment 28 serves to push the cylinder 11 into cylinder 13.

The member 7 is on one hand suitably fastened to the cylinder 13 and on the other hand maintained in place by a piano wire 38 engaged into a groove formed at the uppermost end of the cylinder 11. Similarly, the gaskets 1—2 are maintained in place by piano wires 21 engaged each in a groove formed in the corresponding piston.

Although these different members may be maintained in place in any other way, it is preferred to employ, as abutments, piano wire engaged into annular grooves, even when there is only one groove receiving only one piano wire.

It is to be noted that all cylindrical parts employed are made without any protrusions from their walls, wherefore the fabrication thereof is greatly facilitated.

In Figs. 5 to 10 are illustrated, by way of example, a mechanism and some parts of it for actuating the hydraulic telescoping jack shown in Fig. 4. In Fig. 5, 14 is the casing of the jack, while the movable portion thereof is designated by 11, comprising two pistons. Designated by 18 is the pump adapted to communicate, on the one hand, through a passage 50 with the oil reservoir in the said casing and, on the other hand, through a passage 51 with the cylinder 13 for the jack, said cylinder being adapted to

communicate through the passage 51, a release conduit 51a and a passage 48 in a drainer 49, with the said reservoir. The drainer 49 comprises a valve operating a rod or piston 45 which is urged upwardly by suitable springs and has a head extending through and beyond the upper wall portion of said reservoir. The passage 51a is normally closed by a ball 47 applied against its seat by a suitable spring. For setting in communication the passages 51, 51a and 48, and consequently the interior of the cylinders and the casing, it will be sufficient to press said piston head downwardly in order that the narrow piston end 46 may remove the ball 47 from its seat. When the draining is completed, the pressure on the piston head is released and said communication is then automatically interrupted under the action of the spring.

In order that the desired thrust may be exerted against the piston head 45, the upper portion of the casing 14 is formed with a housing whose upper edge is curved so as to form a shoulder 52. The lever 44, which is intended to actuate the pump 18, is normally engaged into the yoke 53 pivoted as at 54 on the casing 14. For effecting the draining it is sufficient to pull the lever from the left to the right in order that it may pass from its position 44a, in which it has been engaged into the yoke 53, to its position 44 indicated by full lines in Fig. 5. At this instant it suffices to press the lever end, held in the hand, downwardly in order that it may be brought, while pivoting about the point 55, from the position 44 to the position 44b in which this lever presses against the piston head 45.

In order that the end of lever 44 may be maintained in the housing, so that the jack may be withdrawn from under the vehicle after draining, there is provided in the said end a hole 57 (Fig. 6) into which may be engaged a pin 56 made fast to the shoulder 52. Instead of such pin-and-hole arrangement, there may be provided on the casing 14 two protrusions 59, 60 (Figs. 7 and 8) between which may be engaged a pin 61 carried by the lever, or else there may be provided, on the casing 14, two protrusions 63 (Figs. 9 and 10) into which may be engaged a reduced portion 62 or 64 of the lever, and two protrusions 65 into which may be engaged an unreduced portion thereof.

It should be understood that the invention is not limited to the specific details shown, in particular to the shape of the metallic part of gasket or to that of its expandable part or to the manner in which these parts are interconnected, nor is it limited to the particular mechanism described and shown for actuating the lifting jack contemplated, as changes could be effected therein without substantially departing from the spirit of the invention which is intended to be defined by the claims herein.

I claim:

1. In a hydraulic lifting jack of the telescopic type, the combination with a pump, a reservoir for pressure fluid, a fixed cylinder closed at its lower end, passages forming communication between said reservoir and said fixed cylinder by way of the pump, a release conduit for direct flow of fluid between said reservoir and said fixed cylinder, and manually operable means for controlling the flow through said release conduit, of a ram cylinder having a loose fit in said fixed cylinder, a ram having a loose fit in said ram cylinder, said ram cylinder and said ram having an inner end portion of reduced outer diameter

functioning to abut against the bottom of said fixed cylinder, an annular member positioned on said inner end portion of the ram cylinder to guide the same in said fixed cylinder and carrying a packing member having a U-shape in cross-section one leg of which forms a seal with the wall of said fixed cylinder and the other leg of which forms a seal with said inner end portion of the ram cylinder, a second annular member positioned on the inner end portion of said ram to guide the latter in said ram cylinder and carrying a packing member having a U-shape in cross-section one leg of which forms a seal with the wall of said ram cylinder and the other a seal with the inner end portion of said ram, means mounted on the circumferential periphery of said inner end portions to hold said annular members and said packing members in position, and means to limit the upward movement of said ram cylinder and of said ram.

2. A hydraulic lifting jack according to claim 1, wherein the means to hold said annular members and said packing members in position on said inner end portions are constituted by removable spring members inserted in annular grooves provided in the circumferential periphery of said inner end portions.

3. A hydraulic lifting jack according to claim 1, wherein the means to limit the upward movement of said ram and said ram cylinder are constituted by removable co-operating spring members inserted in annular grooves provided, respectively, in the inner wall of said fixed cylinder, in the inner and outer walls of said ram cylinder and in the outer wall of said ram.

4. A hydraulic lifting jack according to claim 1, wherein the manually operable means for con-

trolling the flow through said release conduit includes a spring loaded check valve mounted in said release conduit to prevent flow from the fixed cylinder to the reservoir, a valve operating rod extending outwardly from the jack body arranged to open said check valve against the action of said spring, a removable lever for actuating either said pump or said valve operating rod, pivot means associated with said pump to actuate the same through said lever, and means on said jack body forming a fulcrum point for said lever near said valve operating rod, said fulcrum point permitting to actuate said valve operating rod through said lever independently of said pump actuating pivot means.

JEAN LOUIS GRATZMULLER.
